BOTTLE CLOSURE AND METHOD OF APPLYING SAME

George Weiss, Des Plaines, Ill., assignor to Standard Cap and Seal Corporation, Chicago, Ill., a corporation of Virginia

Application April 4, 1935, Serial No. 14,568

3 Claims. (Cl. 215—38)

This invention relates to improvements in bottle closures, and is more particularly directed to a sanitary closure and seal for bottles and the like, which is applied and secured to the bottle without the use of separate securing means.

With many such closures it has been the general practice to use two or more units, a pre-formed cap and a separate binding or sealing element such as a band or a ring of fixed diameter, the latter being placed around the pre-formed cap and then distorted or contracted by suitable means to force portions of the ring against the cap and the latter against the neck of the bottle, thus leaving the cap with a number of radial projecting portions or folds along the sealing surface.

An object of the invention is to provide a unitary closure formed of paper or other suitable flexible material, that will completely cover the mouth of a bottle, the closure being provided with a uniplanar top portion and a peripheral and cylindrical depending skirt or flange portion of sufficient dimension to fit over the exterior surface of the bottle beading and preferably extend below the point of maximum circumference of the bottle bead, the closure skirt being provided with a non-resilient band secured to and covering a portion thereof, the band being of improved construction, previously formed and cut substantially to length with overlapping ends, one end capable of sliding telescopically within the other end so that the band and peripheral skirt portion can be contracted by any suitable means resulting in an arrangement that will tightly seal a bottle, the sealing portion or inner sealing surface of the closure encompassing and snugly fitting against the bottle being substantially free of kinks, crimps or folds, and making a smooth sealing contact therewith.

Further objects and advantages are within the scope of this invention such as relate to the arrangement, operation and function of the related elements of the structure, to various details of construction and to combination of parts, elements per se, and to economies of manufacture and numerous other features as will be apparent from a consideration of the specification and drawings of a form of the invention, which may be preferred, in which:

Figure I is a side elevation of the neck portion of a form of bottle adapted to contain milk, cream or other fluids and having a closure embodying the invention applied thereto;

Figure II is a view similar to Figure I showing a bottle and closure in partial section, the

closure being arranged in sealing position on the bottle mouth;

Figure III is a view similar to Figure II showing the closure fully applied and secured to a bottle having a modified form of mouth bead; 5

Figure IV is a transverse sectional view taken substantially on line IV—IV of Figure I;

Figure V is an enlarged fragmentary sectional view taken substantially on line V—V of Figure II, illustrating the arrangement of the members 10 when retained in locking position by kinking, pinching or indenting the overlapping portions of the ring;

Figure VI is a vertical sectional view of the paper or flexible cap member forming a part of 15 the closure;

Figure VII is a fragmentary plan view of a section of sheet material suitable for forming a securing band or ring for use as shown in Figures I, II and III; 20

Figure VIII is a vertical sectional view of the non-resilient band member shown in Figure VII, after partial formation for use in connection with and ready to be assembled with the cap member shown in Figure VI; 25

Figure IX is a vertical sectional view of the preformed cap and the preformed non-resilient band member, showing the position of said members for assembling into locking engagement with each other; 30

Figure X is a vertical sectional view of the parts illustrated in Figures VI and VIII in assembled relation;

Figure XI is an enlarged sectional detail view of a portion of the parts shown in Figure X 35 illustrating the assembled relation of the cap and band;

Figure XII is an enlarged vertical sectional view of a portion of the parts illustrated in Figure II showing the application of the closure to 40 a bottle;

Figure XIII is a fragmentary side view of another form of bottle, a conventional sealing cap, and a closure of the present invention in position to be applied upon the bottle; 45

Figure XIV is a view similar to Figure XIII showing a sealing cap applied to the bottle and the sealing closure of my invention in position to be applied over the cap;

Figure XV is a view similar to Figure XIII 50 showing the sealing closure of my invention applied to the bottle;

Figure XVI is an enlarged vertical sectional detail view of the arrangement shown in Figure XV; 55

Figure XVII is a view similar to Figure XVI with a portion of the sealing closure broken away for clearness;

Figure XVIII is a view similar to Figure XVI 5 showing another form of skirted closure of the invention as applied to the bottle;

Figure XIX is a view similar to Figure XVI showing another arrangement of sealing closure and non-resilient band as assembled on a bottle; 10 Figure XX is an enlarged fragmentary detail view of the band illustrated in Figure XIX;

Figure XXI is a perspective view of a bottle with which is incorporated a form of the invention and illustrating a method of removing the 15 sealing closure and cap.

Referring to the drawings in detail, the sealing closure of my invention may be used with or without a disk cap such as is shown in Figure II 20 designated by numeral 5. In a preferred form of the invention, I employ a bottle closure "A" composed of a cap portion "B" formed from paper or other flexible material and having its marginal edge portion embraced or surrounded 25 preferably by a non-resilient metal member "C".

The sealing closure "A" of this invention consists in part of a preformed cap "B" having an imperforate central portion 10 and depending side or skirt portion 11, the marginal edge 12 30 of which carries a non-resilient ring or band member "C". The portion 10 is preferably flat or uniplanar so as to extend over the top of a bottle "D" and on which suitable advertising matter may be printed if desired. The member 35 "C" is preferably formed of metal and substantially U-shaped in cross section with its longitudinal edges securely embedded into the material of skirt member 11 of the closure, thus becoming a permanent part of the closure prior 40 to the application of this unitary structure to a bottle. Such an arrangement provides a sealing closure which can be contracted below the maximum diameter of the beading of bottle mouth 14 and remain as a seal thereon.

45 The member "C" is in the form of an annulus or band of metal 15, as shown in Figure VII, which will readily retain a shape into which it may be formed, bent or pinched. The ring is produced by bending the sheet metal band 15 50 lengthwise upon itself into a U-shaped open tube or trough formation and then reducing this trough-like member into substantially tubular form with one end 16 telescoping into the opposite end 17. The upwardly extending portions of 55 the U-shape may be of the same height, however in the embodiment of my invention illustrated the inner portion 18 is shorter than the outer portion 19. In applying this U-shaped member to the marginal edge 12 or other portion 60 of skirt 11 and exerting pressure upon the edges of the ring by any suitable means the member is pressed into or embedded in the paper closure. As shown in Figures X and XI, the outer wall portion 19 being of greater height than the inner 65 wall portion 18, the edge 21 of portion 19 is projected inwardly and horizontally to overlap the edge 20 of portion 18 and cause the portion 22 of closure skirt 11 to assume a substantial horizontal or offset position. Thus a substantially tubular 70 circular ring is formed with telescoping ends which are frictionally interlocked, and the edges of which are securely embedded into the paper skirt 11.

In Figures XIII to XXI the invention has been 75 illustrated as incorporated for use on another

type of bottle. The bottle D—I is adaptable for use in the packaging of beverages and is preferably hermetically sealed by means such as a metal crown cap 50 fluted or crimped as at 51. The crimped portions 51 are pressed into close 5 contact with the bead 53 and the recess 55 adjacent thereto of the bottle, a suitable sealing gasket of cork 56 or other material being positioned between the interior of the cap 50 and the lip of the bottle. In many instances, bottles sealed only in this manner present an unfinished 10 appearance and in addition such caps can be removed and replaced without detection, permitting contamination or surreptitious refilling. However, by applying a sealing closure of this 15 invention over such crown caps, a tamper proof seal is provided. Figures XIII to XV show a closure sealing arrangement wherein bottle D—I first receives the crown cap 50 and a sealing closure 60. The closure 60 is preferably initially 20 preformed with a flat top surface 61 and a depending or skirt portion 63. The edge 64 of skirt 63 has applied thereto a formed band or ring 65 preferably of tubular configuration, generally U-shaped in cross section. The extremities 66 and 25 67 of the ring 65 are telescoped so that one end fits snugly within the other and the edges 68 and 69 of the ring embedded within the closure material which may be of paper or other flexible material. In this instance the closure 60 with the 30 ring 65 previously formed therewith is applied over the crown cap 50 and the skirt and ring contracted beneath the maximum diameter of the bottle mouth bead 53 and of the crown cap 50 35 as well. As shown in detail in Figures XVI and XVII the crimped portion 51 of crown cap 50 flares outwardly adjacent the recess 55 and the skirt portion of closure 60 lies beneath the crimped portion, the ring 65 being contracted into the recess 55. Thus, it will be noted that in 40 order to remove the crown cap 50 the closure 60 be also removed at the same time which removal distorts the ring or mutilates the closure. In either instance closure 60 cannot be replaced 45 without indicating that the closure has been previously removed. When an opener such as is illustrated in Figure XXI is used, both caps will be removed together, and in so doing, the sealing closure 60 is either mutilated or distorted due to the action of the opener in prying the 50 cap 50 loose.

Figure XVIII illustrates another form of the invention wherein a cap 50 serves to hermetically close the bottle D—I and sealing closure 60' 55 covers the cap 50. The closure 60' is provided with an elongated skirt portion 70 which extends to a position below an annular projection or bead 72 formed on the exterior surface of the bottle adjacent a recess 73. In this instance a ring 65' is contracted beneath the maximum 60 diameter of the bead 72. Removal of the cap 50 or closure 60' necessitates the destruction or mutilation of the closure 60' or the separation or distortion of the end portions of the ring 65', thus preventing its reuse.

In some instances it may be desirable that the exterior sealing closure be maintained intact upon removal and in order to do this, a form of ring 80 having an inner wall 81 higher than the forms hereinbefore described may be used. As 70 shown in Figure XX, this form of ring provides a wall or surface 81 which is engageable with the crimped portion 85 on the cap 84 so that the irregular surface formed by the crimping engages the ring 80, as illustrated in Figure XIX. 75

The skirt portion 87 of the closure 86 is embraced by the ring in a manner similar to the other forms described and is in effect integral therewith. The ends of the ring 80 are telescoped 5 and upon application to the bottle and cap 84 the ring is contracted in a manner to be hereinafter explained so that its diameter is less than that of the maximum diameter of the cap 84. Thus removal of the sealing closure 86 from the cap 10 84 necessitates separation or distortion of the ring ends. By the use of paper or similar fibrous or flexible material for the closure 86, it is to be noted that should an opener such as is illustrated in Figure XXI be used to remove the cap 15 and closure, the latter will be so disfigured or mutilated that its reuse without detection is not likely. This is due to the fact that the prying action of the opener will either separate the band ends or rupture the closure top or skirt portion. 20 The application and sealing of the closure on the type of bottle shown in Figures I to III will now be described. In practice, in the packaging of milk, the bottles are fed by hand or by a traveling conveyor to a closure applying station, 25 closures are placed upon the bottles by hand or by automatic closure applying means employing a feeding tube or chute containing closures in serial formation, the bottles with loose closures applied thereon are then fed by hand or automatic means to a closure securing or sealing apparatus. Dies or jaws (not shown) subsequently operate upon the positioned bottle and closure, 30 pressing the closure "B" and its ring "C" tightly over the mouth of the bottle and into contact 35 with the exterior surface of the bottle bead. Such action contracts the ring member "C" by circumferentially shortening the same by forcing or wedging the one end 16 into the other end 17 of the ring. The end 16 slides telescoping 40 cally within the end 17 forming a telescoping joint which causes only a slight fold, or overlap of the paper skirt portion 11, the closure becoming approximately the shape illustrated in Figure I and in this manner seals the latter upon the 45 bottle bead. The telescoping joint will be held secure by the wedging of the end portions telescoping and by the additional squeezing or flattening of the tubular ring. As a further means of insuring the telescoping joint against 50 reopening, the dies or other means of the closure sealing means may be formed with projections causing indentations or depressions 23 in the telescoping portion of the joint or if desired, entirely throughout the circumference of the ring 55 as shown by Figures III and V. In each instance, the non-resilient split metal band is tightened or contracted by telescoping the ends of the band. Thus, in use the unitary closure consisting of the skirted cap and split metallic 60 ring united to the marginal edge is first applied to the bottle. Then by suitable apparatus as above described the skirt and band are contracted and secured upon the bottle in sealing en-

gagement with the bottle bead surface by interlocking the end portions of the ring together, the sealing portion or inner surface of the ring snugly fitting the bottle bead, free of kinks or folds. 5

When packaging beverages or the like in bottles of the character shown in Figures XIII to XXI, the bottles may be fed in the manner hereinbefore described to a cap applying station where the crown caps are applied. The capped bottle may 10 then receive the outer closure which is sealed thereon by suitable mechanism to telescope the ends of the ring so that the closure is maintained in fixed position with respect to the crown cap and bottle mouth. In this instance the ring and the skirted portion of the closure are tightened or contracted to a lesser diameter about the bottle and in removing the same from the bottle or the cap ordinarily the telescoping ends of the band will be retracted partially, or wholly separated. 15 Should the band ends remain in their sealed position, the cap may be removed by a destruction of the closure material or separation thereof from the band or ring. Thus a closure has been provided to effectively cover the mouth of a bottle 20 and prevent unauthorized tampering with the contents thereof. 25

It is apparent that, within the scope of the invention, modifications and different arrangements may be made other than is herein disclosed, 30 and the present disclosure is illustrative merely, the invention comprehending all variations thereof.

What I claim is:

1. A unitary closure for containers including a cap formed with a skirt portion; a non-resilient locking ring frictionally clamped to the edge portion of said skirt, said ring having interengaging ends for sealing said closure upon a container. 35
2. A unitary closure for containers including a cap having a skirt, and a locking ring frictionally clamped to an edge portion of said skirt, said ring having interengaging ends adapted to slide telescopingly one within the other and be interlocked by non-restorable deformation of said ring end 40 portions. 45
3. A unitary closure for bottles, including in combination a cap; a locking ring therefor; said cap composed of flexible material having a uniplanar top portion and a peripheral skirt portion 50 with a normal inside diameter equal to or greater than the maximum exterior diameter of a bottle mouth beading; said skirt being of insufficient length to extend below the bottle bead; said ring comprising a split metallic member frictionally 55 clamped to the peripheral edge of said skirt, the ends of said ring being engageable as the cap and ring are contracted into engagement with and below the maximum diameter of the bottle bead, said engageable ends being frictionally interlocked to normally retain the cap on a bottle. 60

GEORGE WEISS.
